BUTYROMETER CENTRIFUGE

Gustaf Wilhelm Ruda, Stockholm, Sweden, assignor to Aktiebolaget Separator, Stockholm, Sweden, a corporation of Sweden

Application December 12, 1946, Serial No. 715,789
In Sweden March 1, 1945

4 Claims. (Cl. 233—26)

1

This invention relates to butyrometer centrifuges in which test tubes containing the butyrometer samples are held in the centrifugal bowl by means of a rack comprising superimposed plates defining radial pockets for the test tubes.

When using butyrometer centrifuges, water is let into the centrifugal bowl in such a way as to flow radially outward from a central tube in the bowl to the outer wall of the bowl, and from there inward until the bowl is filled up to a certain level situated a little outside the inwardly directed mouths in the necks of the test tubes. The water thus introduced into the bowl serves to control the temperature of the contents of the test tubes. It is important that water is not admitted into the mouths of the test tubes before the centrifugation. Therefore, the level to which the bowl is filled with water should under no circumstances be allowed to lie inside the mouths before the centrifugation. To prevent this, the bowl is provided with an overflow discharge or water outlet at a suitable distance from the axis of rotation of the bowl. The water level, of course, tends to adjust itself at the same radius as this overflow discharge. However, with butyrometer centrifuges as constructed heretofore, it has been found in practice that the water level in the vicinity of the inlet to the bowl chamber for receiving the test tubes will, under certain circumstances, be located too far inwardly and, in fact, inside the test tube mouths. This often causes water to flow into the mouths of some of the test tubes, causing a liquid exchange between the content of the tubes and the water mass around them. Part of the milk fat in the test tube will then escape, with the result that the fat content in the tube, as measured after the centrifuging has been finished, will be less than what corresponds to the original fat content in the tube. The test will thus be erroneous.

The present invention, therefore, is directed to the provision of an improved butyrometer centrifuge which will overcome the above-mentioned difficulty. According to the invention, the bowl of the butyrometer centrifuge is provided with conveyors which insure complete conveying of the water from its inlet openings outwardly toward the outer portion of the bowl and then inwardly toward the overflow discharge. In this way, the conveyors act upon the water mass on its way through the bowl, to cause the water mass to rotate at the same angular speed as the bowl and thus prevent slipping, whereby the centrifugal force will affect all portions of the water mass in the same degree. Accordingly, the level of the

2

water mass in the bowl will adjust itself substantially parallel to the axis of rotation and will not reach the mouths of the test tubes by moving inside the radius of the overflow discharge.

5 The conveyors may conveniently be made in the form of wings attached to the bowl top or cover and to the bottom of the bowl and extending, respectively, to the uppermost and lowermost plates of the holder rack. Alternatively, 10 the wings may be attached wholly or partly to the holder plates instead of the bowl walls.

For a better understanding of the invention, reference may be had to the accompanying drawing, in which

15 Fig. 1 is a vertical sectional view, partly in elevation, of one form of a centrifugal bowl arranged in accordance with the invention;

Figs. 2 is a vertical sectional view, taken on line 2—2 of Fig. 4, of part of the bowl illustrated in 20 Fig. 1, showing in detail the manner of arranging the conveyor wings above the uppermost holder plate;

Fig. 3 is a view similar to Fig. 2 but taken on line 3—3 of Fig. 4, showing the manner of arranging the conveyor wings below the lowermost holder plate, and

Fig. 4 is a plan view of one of the intermediate plates shown in Fig. 1.

30 Referring to the drawing, the numeral 10 designates a centrifugal bowl adapted to be rotated about a central vertical axis, as by means of a driving spindle 11. Within the bowl is a rack comprising a plurality of superimposed plates 12, 35 the lowermost of which has a driving connection from the bowl in the form of a hole 13a (Fig. 4) which receives a driving pin 13 seated in the bottom of the bowl. Each of the plates 12 has a peripheral driving and locating pin 14 engaged in

40 a downwardly directed slot in the side wall of the next upper plate, whereby the nested plates are driven as a unit. Each pair of adjacent plates 12 defines a horizontal series of circumferentially spaced pockets 15 which are staggered with respect to the pockets in the next horizontal series. The pockets 15 are shaped to hold the test tubes 16 in radial positions, with the necks and mouths of the respective tubes located near the axis of rotation.

Above the bowl 10 is a stationary water container 18 provided with a bottom valve 19 and a discharge pipe 20. The valve 19 is operable manually to control the flow of water from the tank down through the pipe 20 and into the upper end 55 of an inlet tube or tubular shaft 21 in the bowl.

The tubular shaft 21 is connected with and located centrally in the bowl and projects upwardly through a neck 22a on the bowl top or cover 22. From the neck 22a, the tubular shaft 21 extends downwardly through central openings in the holder plates 12, the lower end receiving the upper end of a nut 11a threaded on the driving spindle 11. Immediately below the cover 22, the tubular shaft 21 is provided with one or more side openings 21a through which water flows radially outward into the bowl chamber containing the test tubes 16, the water filling the bowl chamber up to the level 23 defined by the discharge holes 24a in the plates. Thus, any additional water introduced through the inlet 21a, beyond that necessary to maintain the bowl chamber filled to the level 23, will discharge from the bowl chamber by way of these holes and be conducted therethrough to an overflow discharge chamber 24 and leave the bowl through an outlet 25.

In order that the water jet from the inlet opening 21a shall continue in the radial direction in relation to the bowl, an effective conveying of the water is required along its whole passage. To provide such a conveying, wings 27 are arranged radially between the uppermost plate 12 and the bowl top or cover 22, the conveying wings extending from the vicinity of the tubular shaft 21 outwardly to the outer portion of the bowl. As illustrated, each wing is divided along a plane 28 forming the inside of the bowl cover 22. The part of wing 27 located below the plane 28 is attached to the uppermost plate 12, while the portion 29 above the plane 28 is attached to the bowl cover 22.

The outer part of the uppermost plate 12 has a number of holes 30 for admitting water into the space between the two uppermost plates. It will be understood that through corresponding holes 30a in the plates below, the water passes on to the intermediate spaces between these plates. Each of the holder plates below the uppermost plate 12 is suitably provided with conveyor wings 27a.

The lowermost plate 12 rests directly on the bottom of the bowl. The tube pockets formed in the lower face of this plate serve as effective conveyors along the major part of the water path from the outer portion of the bowl to the overflow discharge 24. However, the region outside but adjacent to the overflow discharge is not covered by these pockets. Accordingly, in order to convey the water along this region as well, I provide a plurality of wings 32 which form radial extensions leading directly to the overflow discharge 24. As pointed out above, the wings 32 may be attached to the bottom of the bowl or they may be attached to the lowermost plate 12.

By arranging the wings 27 near the top of the bowl and the wings 32 near the bottom of the bowl, and affixing the wings 27a between the plate 12, all in the manner described, I provide effective conveyors radiating from the regions of the water inlet and the water outlet, respectively, of the bowl, which act to cause the flowing water mass to rotate at the same angular velocity as the bowl. As a result, the water level 23 in the bowl during the centrifuging is maintained in such a manner as to prevent the water from reaching the mouths of the test tubes and causing a liquid exchange with the contents of the tubes.

I claim:

1. In combination with a centrifugal bowl, a

tube holding rack in the bowl including a plurality of superimposed plates defining pockets for receiving test tubes, the plates having liquid flow passages extending through generally horizontal surfaces of the plates for serial flow of liquid through the pockets, the bowl having inlet and outlet openings for flowing a liquid into the bowl, through the passages and pockets, and out of the bowl, and a plurality of radial conveying elements extending from the rack to the upper wall of the bowl and from the rack to the lower wall of the bowl, said elements defining upper and lower channels communicating with said openings, respectively, and also with said passages, said conveying elements including wings secured to the uppermost plate of the rack and extending substantially radially with respect to the rotation axis of the bowl, said elements acting to bring about correspondence between the angular speed of the liquid flowing through the bowl and the angular speed of the bowl during the centrifuging.

2. In combination with a centrifugal bowl, a tube holding rack in the bowl including a plurality of superimposed plates defining pockets for receiving test tubes, the plates having liquid flow passages extending through generally horizontal surfaces of the plates for serial flow of liquid through the pockets, the bowl having inlet and outlet openings for flowing a liquid into the bowl, through the passages and pockets, and out of the bowl, and a plurality of radial conveying elements extending from the rack to the upper wall of the bowl and from the rack to the lower wall of the bowl, said elements defining upper and lower channels communicating with said openings, respectively, and also with said passages, the conveying elements including a wing fixed to one of the end plates of the rack, and an aligned wing fixed to the adjacent horizontal wall of the bowl, said elements acting to bring about correspondence between the angular speed of the liquid flowing through the bowl and the angular speed of the bowl during the centrifuging.

3. In combination with a centrifugal bowl, a tube holding rack in the bowl including a plurality of superimposed plates defining pockets for receiving test tubes, the plates having liquid flow passages extending through generally horizontal surfaces of the plates for serial flow of liquid through the pockets, the bowl having inlet and outlet openings for flowing a liquid into the bowl, through the passages and pockets, and out of the bowl, and a plurality of radial conveying elements extending from the rack to the upper wall of the bowl and from the rack to the lower wall of the bowl, said elements defining upper and lower channels communicating with said openings, respectively, and also with said passages, the upper wall of the bowl being in the form of a removable cover, the conveying elements at the top of the bowl including a wing fixed to the uppermost plate of the rack, and an aligned wing fixed to the cover, said elements acting to bring about correspondence between the angular speed of the liquid flowing through the bowl and the angular speed of the bowl during the centrifuging.

4. In combination with a centrifugal bowl, a tube holding rack in the bowl including a plurality of superimposed plates defining pockets for receiving test tubes, the plates having liquid flow passages extending through generally horizontal surfaces of the plates for serial flow of

liquid through the pockets, the bowl having inlet and outlet openings for flowing a liquid into the bowl, through the passages and pockets, and out of the bowl, and a plurality of radial conveying elements extending from the rack to the upper wall of the bowl and from the rack to the lower wall of the bowl, said elements defining upper and lower channels communicating with said openings, respectively, and also with said passages, the conveying elements at the bottom of the bowl including relatively short wings fixed to the lowermost plate of the rack, said elements acting to bring about correspondence between the angular speed of the liquid flowing through the bowl and the angular speed of the bowl during the centrifuging.
